DOLL WITH MOVABLE ARMS

Yolanda Helen Musselwhite and Joseph A. Musselwhite, Washington, D. C.

Application July 25, 1949, Serial No. 106,674

4 Claims. (Cl. 46—119)

1

This invention relates to a doll of the type having a body carrying movable arms and legs and one object of the invention is to provide such a doll with means for imparting movements to the arms in such a manner that they may be caused to move transversely of the body of the doll and imitate movements of a baby's arms when clapping its hands and playing "patticake."

Another object of the invention is to provide a doll with arm moving means which is embedded in the body of the doll and thus hidden from view as well as being prevented from protruding from the doll. It will thus be seen that the doll may be conveniently held in a person's arms or disposed in a reclining position upon its back without its arms being accidentally caused to move.

Another object of the invention is to provide an arm moving mechanism which is actuated by pressure upon a button at the rear of the mechanism, the button being located at the back of the doll's body in such position pressure may be applied to the button by a finger of a hand supporting the doll at the back thereof or by pressing upon the front of the doll when the doll is in a reclining position.

Another object of the invention is to provide arm moving mechanism including a casing which is mounted horizontally in the body of the doll and arm-engaging members which are movably carried by the casing and formed from a strip of resilient metal which is bent to form the arm-engaging members and also forms a handle or shank connecting the arm-engaging members projecting rearwardly from the casing and carrying a button at its rear end.

Another object of the invention is to provide arm moving mechanism for a doll which is simple in construction and will not add materially to the weight of the doll, the device being of such construction that it may be incorporated in a doll of conventional construction.

The invention is illustrated in the accompanying drawings wherein:

Fig. 1 is a view showing the body and arms of a doll in cross section and the arm operating means in top plan and holding the arms in their normal position.

Fig. 2 is a vertical sectional view taken along the line 2-2 of Figure 1.

2

Fig. 3 is a fragmentary sectional view taken along the line 3-3 of Figure 1.

Fig. 4 is a view similar to Figure 1 showing the arms of the doll spread apart.

5. Fig. 5 is a perspective view of the arm operating means.

The doll with which the improved arm-moving means is incorporated has a body 1 which may be of any size desired and has a fabric casing 2 filled with cotton batting 3, or other suitable material, which forms a soft and compressible body for the doll. The usual legs and head (not shown) are provided and the usual arms 4 are also provided. These arms have hollow lower-arm portions 5 terminating in hands 6, the upper portions 7 of the arms being formed of fabric and filled with portions 3' of the cotton with which the body is filled. After the body has been filled with cotton to the level of the arms, the arm-operating means 8 is inserted through the open top of the body and the filling of the body then completed and its upper end secured about the neck of the head. It will thus be seen that the arm-operating device will be embedded in the body at the level of the arms, as shown in Figures 2 and 4, and will be prevented from moving out of its proper position by the stuffing with which the body is filled.

30 which the body is lined. The arm-operating device is illustrated in Figure 5 and referring to this figure it will be seen
35 that it has a casing 9 consisting of upper and lower substantially heart-shaped walls 10 held in spaced relation to each other by a marginal edge wall 11. The casing may be formed of any suitable material but its walls are preferably formed of plastic which is of light weight but quite stiff so that the casing will be prevented from collapsing. The casing is open across its rear portion since ends of the side edge wall terminate at opposite sides of the rear portion of the casing and in forwardly spaced relation to its rear ends the marginal edge wall is formed with openings 12 so located that they register with inner ends of the hollow upper arm portions 7. Midway the width of the open rear end of the casing the upper and lower walls 10 are formed with forwardly projecting recesses 13. A movable member 14 is carried by the casing and is formed from a strip of this resilient metal which is bent 40 to form a shank 15 and arms 16. The interme- 45

diate portion of the resilient strip which forms the shank 15 has its forwardly extending side portions secured together by a binding 17 and upon the rear bridge portion of the shank is mounted a button 18 which is preferably formed of plastic and has a reduced and squared forward portion 19 through which an opening 20 is formed to accommodate the bridge of the shank. The arms 16 extend laterally away from each other in front of the binding 17 and are 10 curved forwardly and inwardly and have their front end portions bent inwardly back upon themselves and secured by bindings 21 to provide the arms 16 with yieldable forward portions 22 which allow the arms to be easily thrust into the arms of the doll and have frictional binding engagement with the forward portions 5 of the doll's arms. Resiliency of the metal strip from which the movable member is formed causes it to normally remain in the position shown in Figure 1 with the hands 6 of the doll close to each other and the shank projecting rearwardly from the casing. The button is held flat against the inner surface of the fabric casing 2 at the back of the body 1, and referring to Figures 1 and 4 it will be seen that the button is of such dimensions that when it is pressed forwardly it may enter the recesses 13. This allows the button to be forced forwardly a sufficient distance to cause the arms 16 of the actuating member 14 to be shifted to the position shown in Figure 4. During movement of the arms 16 from the position shown in Figure 1 to that of Figure 4 the arms bear against the front ends of the openings 12 and have a rocking and sliding movement along these front edges. This sliding and rocking movement of the arms 16 causes the arms of the doll to be swung outwardly away from each other and when pressure upon the button is removed resiliency of the arms 16 cause the doll's arms to swing towards each other and return to the position shown in Figure 1. When the pressure is alternately applied to and removed from the button the doll's arms will perform a series of movements towards and away from each other and "patticake" movements will take place which will be very pleasing to a little girl playing with the doll. The doll may be held in the arms of a person playing with it and pressure applied to the button by a hand holding the back of the doll or the doll may be placed in a reclining position upon its back in a doll carriage or bed and when pressure is applied to the front of the doll's body and actuating member 14 will be shifted forwardly and rearwardly to effect movements of the doll's arms.

While a preferred embodiment of the invention has been illustrated and described it will be understood that variations in construction such as come within the scope of the accompanying claims are contemplated.

Having thus described the invention, what is claimed is:

1. In a doll, a body having a fabric casing and a soft filling for the casing, arms having inner arm-portions forming continuations of the body and movably connecting the arms with the body and hollow outer arm-portions formed of stiff material, and an actuator for said arms embedded in the body and comprising a shell open at its rear and formed with side openings, a shank passing through the rear opening of said shell and having its rear end bearing against the inner surface of the fabric casing, and yieldable arms extending from the front end of said shank

5 outwardly through the side openings of the shell and into the arms of the doll and frictionally gripping the hollow outer portions thereof, the said arms of the actuator adapted to be rocked transversely of the body across edges of the side openings and thereby imparting "patticake" movements to the arms of the doll towards and away from each other when reciprocating movements are imparted to the shank by pressure upon its rear end.

2. In a doll, a body having a fabric casing and a soft filling for the casing, arms having hollow portions and flexible connections between inner ends of the arms and sides of the body, and an actuator for said arms comprising a shell embedded in the filling and having a rear opening and side openings opposite inner ends of said arms, a shank passing through the rear opening and projecting rearwardly from the shell with its rear end bearing against the inner surface of a portion of the fabric casing at the back of the body, and resilient actuating arms extending laterally from the front end of the shank and passing through the side openings and forwardly into the arms of the doll longitudinally thereof and frictionally gripping the arms of the doll, the resilient arms normally extending forwardly in converging relation to each other and thereby urging the doll arms towards each other, and said resilient arms being slid through the arms and the side openings and rocked across front ends of the side openings in a direction away from each other when pressure is applied to the rear end of the shank and thereby serving to swing the doll arms away from each other, and the said actuating arms returning to their normal positions to move the doll arms towards each other when pressure is removed from the rear end of the shank.

3. In a doll, a body having a fabric casing and a soft filling for the casing, arms having hollow portions and flexible connections between inner ends of the arms and sides of the body, and an actuator for said arms comprising a shell embedded in the filling and having upper and lower walls and a rear opening and side openings opposite inner ends of said arms, a strip of resilient metal folded midway its length and secured to form a shank and arms extending from the front end of the shank, the arms formed by said resilient strip extending laterally away from opposite sides of the shank and through the side openings of the shell and into the doll arms longitudinally thereof with their forward portions folded inwardly back upon themselves and secured to form compressible portions having frictional binding engagement with inner surfaces of the hollow portions of the doll arms, and a button carried by the rear end of the shank and bearing against the inner surface of a portion of the fabric casing at the back of the body, resiliency of the arms formed by the resilient strip urging the shank rearwardly and the arms of the doll towards each other, said shank when forced forwardly by pressure upon the button flexing portions of the resilient arms within the shell forwardly and rocking the said resilient arms across front ends of the side openings to swing the doll arms away from each other and thereby impart patticake movements to the doll arms during forward and rearward movements of the shank.

4. A device for imparting movement towards and away from each other to movable members

projecting from the body of a figure toy, said device comprising a shell having openings at opposite sides thereof and a rear opening, a strip of resilient material bent intermediate its length and forming a shank and yieldable arms integral therewith, said shank being disposed within the shell and shiftable forwardly and rearwardly therein and said arms extending laterally from opposite sides of said shank and passing outwardly from the shell through the side openings and having outer portions adapted for engagement with the movable members, the said arms having sliding and rocking movement imparted to them across edges of the side opening

5 for operating the said members when the shank is shifted longitudinally.
